UNITED STATES PATENT OFFICE.

ABRAHAM LAZARSON, OF CHICAGO, ILLINOIS, ASSIGNOR TO SAMUEL STEIN, OF CHICAGO, ILLINOIS.

GAS-LAMP.

1,188,661.

Specification of Letters Patent. Patented June 27, 1916.

Application filed May 27, 1914. Serial No. 841,197.

To all whom it may concern:

Be it known that I, ABRAHAM LAZARSON, a subject of the Czar of Russia, residing at the city of Chicago, in the county of Cook 5 and State of Illinois, have invented certain new and useful Improvements in Gas-Lamps, of which the following is a specification.

My invention relates to the mechanisms 10 or devices used for burning illuminating gas mixed with atmospheric air, thereby producing a high degree of heat by which mantles of refractory material are heated to incandescence. It is especially applicable to 15 that class thereof which are commonly called "arc lights" and in which one or more inverted mantles are placed at the lower part of the apparatus. This class of lights is generally hung high in store buildings and 20 the like, and during the time they are out of service a pilot light is usually kept burning adjacent to the principal or main burners ready to ignite the gas when turned into them. The performance of these functions 25 is usually controlled by a main valve operated by a chain attached thereto and depending into convenient reach.

It is the object of my invention, among other things, to provide a simple and efficient 30 mechanism for regulating the main gas valve. I also provide an improved means by which the mixed volume of gas and air is regulated at a point adjacent to the burner and by which also regulation of 35 the flame and protection against "flash-backs" can be positively avoided without the use of screens. There are also convenient and effective devices for regulating the flow 40 of gas and air to the mixing tube, for protecting the main valve from the heat of the burner, and for arresting the foreign matters which are brought into the lamp with the gas before they reach the burners.

My invention also includes improved 45 forms and arrangements of the parts by which the whole device is made more simple and repairs and attachments are more readily and conveniently effected, the novel features of which are more fully set out 50 in the detailed description and claims.

The principles of my invention are illustrated in the drawings, in which—

Figure 1 is a vertical section of the entire apparatus; Fig. 2 is a section of the 55 main valve stem taken on the line 2—2 of

Fig. 3; Fig. 3 is a top view of the apparatus; Fig. 4 is an enlarged detail of the central union with its connections and adjustments; Fig. 5 is a section of Fig. 4 on the line 5—5; Fig. 6 is a side elevation of 60 the chimney shown in Fig. 1, looked at from the left; and Fig. 7 shows the outer end of the mixing tube.

Further describing my invention with reference to the drawings, in which like 65 characters of reference denote like parts throughout: 1 is the main valve casing of my device having the longitudinal bore 2. A valve plug 3 is transversely mounted therein having the cross-bore 4 there- 70

5 is a dependent pipe connected with the main source of gas supply, to which the valve casing is attached. A four-toothed ratchet 6 is mounted or integrally formed 75 on the valve stem and a lever 7 is also loosely mounted on the said valve plug. A spring 8 is coiled on the valve plug outside the lever, and is held in place by the screw 9 which takes into the end of 80 the main valve stem. One end of the said spring is attached to an arm 10 extended outwardly from the valve casing, and the other end of said spring engages at 11 on the underside of the lever 7 to hold it in 85 the illustrated position. A gravity actuated dog 12 is pivoted at 13 upon the said lever and the hook thereof is adapted to engage with the teeth upon the ratchet 6. A plurality of upward projections 14 and 15 90 on the lever 7 are adapted to engage with the arm 10, thereby limiting the movement of the lever in each direction, while an upward projection 16 having the transversely extended portion 17 limits the 95 upward movement of the dog 12. A nipple 18, having the adjusting screw 19 is threaded into the upper part of the casing so as to receive a flow of gas from the main source of gas supply through the nipple and into the pilot light connection 20.

The main valve is shown in the illustration as open, the cross-bore in the plug being in alignment with the longitudinal bore in the casing. When the long arm of lever 7 is depressed from the position illustrated the transverse opening in the plug should be at right angles to the casing, this being provided for by the relation of projections 14 and 15 to the arm 10. As the lever is 100 105 110

- released it moves to the position shown under the pull of spring 8, the dog 12 engages the next notch on the ratchet and a succeeding down pull turns the plug 5 through another quarter revolution, thereby again opening the valve and allowing the gas to flow downward, being further controlled in its passage by the devices hereafter to be explained.
- 10 A link 21 connects the nipple 22 with the valve casing 1 above described. On the lower end of the nipple 22 is a union 23, having the vertical body portion 24, from the upper portion of which leads the outlet off-set 25 and into which at the lower portion leads the inlet off-set 26. The vertical portion is provided with a transverse partition 27, above which is formed a receiving pocket or trap 28. The outlet off-set 25 has an extension 29, having the longitudinal bore 30 for a portion of its length and a transverse outlet 31 connected therewith. The outer end of said extension is threaded at 32 and a nut 33 is fitted thereon. The bore of the inlet off-set 26 is enlarged adjacent to its outer end to form an inside annular shoulder 34. The inner end of the mixing tube 35 is seated in said enlarged portion, while the outer end at 36 is flaring or funnel shaped.
- 15 The said flaring portion may be formed integrally with the body of the mixing tube or separately constructed and attached thereto as desired. Across the outer end thereof is a support 37, having a central opening 38 and a notch 39 in its upper edge. A reversely curved connecting member having a body portion 40 is provided with a thimble 41 at its upper extremity, which is adapted to pass over the extension 29 of the outlet off-set. It has a central opening 42 which in assembling the parts should be in alignment with the outlet opening 31 in the extension 39. The lower end of said member 40 has an enlarged portion 43, in the outer end of which is screw threaded a needle valve 44. Into the other end of said enlargement is threaded a nipple 45 having a tapered opening 46, which forms a seat for the point 47 of the needle valve. In assembling the parts the head of said nipple passes into the opening 38 of the cross member 37 of the mixing tube and the shoulders of said enlarged portion rest upon said cross member. The body 40 rests in the notch 39 and the thimble 41 is passed over the plug 29. When the nut 33 is turned home all the said movable parts are clamped securely in their normal position. A sleeve 45' is slidably mounted in the mixing tube 35 and a slot 46' is cut in the underside thereof through which, to make connection with the said sleeve, is extended the screw threaded portion 47' of the connecting member 48. The latter is secured at right angles by means of the nuts 49 and 50 to the end of a screw
- 20 threaded member 51, which is threaded into the downwardly extended projection 52 of the mixing tube.
- 25 A cup shaped stationary valve seat 53 with the tapering walls 54 is secured in the inlet opening of the main union 23 by means of the radial arms 55 which rest on the annular shoulders therein and are held in place by the inner end of the mixing tube 35. The said valve seat is preferably made of sheet metal and may be stamped therefrom so that the body is hollow and the concave side should be turned in the direction of the gas flow; that is, toward the burner. It thus becomes an efficient stop to prevent the flame 80 from being carried back to the needle valve. It will be seen that by turning the screw 51 the sleeve 45 may be moved inwardly or outwardly, while the inward end thereof forms with reference to the valve 53 an annular 85 opening which will be reduced or enlarged as the position of the sleeve is changed. As the flow of gas is regulated by the needle valve, the movement of the sleeve 45 which changes the size of the opening between it and the valve 53 will regulate the amount of air admitted to the burner and also the property of the mixture. The convenient relations of the needle valve and of the mixing tube valve, make it convenient as well as 90 possible to make a mixture that will give perfect combustion.
- 30 In order that the main valve may be protected against the intense heat coming directly from the burner or burners, I provide a chimney, shown in Fig. 6, having the vertical walls 56 and the cover 57 therefor. The cover is secured to the main walls by the connections 58 so as to leave a free annular opening 59. The lower part of the chimney stands upon the transverse supports 60, the nipple 22 passes through a central opening in the top and the link 21 screwed down onto the top holds the chimney firmly in place upon the support 60. 100 Side openings 25' and 26' are provided through which the outlet and inlet openings of the main union may be passed. A burner or burners 61 is extended downwardly from the main union 23; such burner or burners 115 may be provided with a globe or shade 62, as desired, and the principal parts are enclosed by the casing 63 narrowed midway of the top and bottom into close relation with the chimney 56. It will be seen that 120 the stream of gas being established at the main valve flows to the heated central portion, where the cup 28 receives any non-volatile elements which may be removed. It then passes through the outlet 25 and the 125 connecting member 40 to the needle valve 45 where the absolute amount is regulated, thence through the mixing tube and the mixing tube valve to the burner. It is then lighted by the pilot light of the connection 130

20, by which the burners are kept at all times moderately heated. It is of great importance in giving long life to the mantles of this class of burners that "flash-backs" 5 should be avoided, and that when once lighted the final heat shall be quickly established and held steadily at that point. It also adds greatly to the efficiency of the 10 gas consumed to deliver the mixture to the burner in a highly heated condition. As the central union, with the mixing tube valve, of thin metal as described, and a part of the mixing tube itself are inclosed in the chimney 56, the heated upward currents in 15 the chimney quickly raise the said parts to and keep them at a high temperature. The result is increased efficiency of gas and added life of the mantles.

I claim:

- 20 1. In a gas lamp; the combination with a source of gas supply and a burner, of a union having an outlet offset, an extension member secured to said offset, an inlet offset, having a recessed seat, a mixing tube seated 25 in the inlet offset and having a flaring outer end with a peripheral notch, a connecting member having a thimble at its upper end to fit over the extension member, means at its lower end to engage the mixing tube and 30 adapted to engage with the said peripheral notch, a needle valve in said connecting member to regulate the flow of gas to the mixing tube, and means to secure the connecting member to the extension member 35 whereby the mixing tube is held in its seat.
2. In a gas lamp; the combination with a mixing tube adapted to receive air at its outer portion, of means for introducing and

regulating a flow of gas thereto, a valve member in fixed relation to the inner end of 40 said tube and a valve member in the tube movable therein relatively to the fixed member for regulating the flow of mixed gas and air to the burner.

3. In a gas lamp; the combination of a 45 mixing tube adapted to receive air at its outer portion, of means for introducing and regulating the flow of gas thereinto, a fixed tapering valve member at the other end of 50 said tube, a sleeve slidable in the mixing tube, and means for adjusting said sleeve relatively to the said valve member.

4. In a gas lamp; the combination of a 55 mixing tube adapted to receive air at its outer portion, of means for introducing and regulating the flow of gas thereinto, a hollow tapering valve member at the other end 60 of said tube, a sleeve slidable in the tube, and means for adjusting said sleeve relatively to the said valve member.

5. In a gas lamp; the combination with a union provided with an inlet offset having an inside annular shoulder, of a valve member having radial arms seated on said shoulder, a mixing tube with its inner end resting on said radial arms, and a sleeve longitudinally movable in the mixing tube and 65 adjustable relatively to said valve member.

In witness whereof, I have hereunto subscribed my name, this 25th day of May, 70 1914, in the presence of two subscribing witnesses.

ABRAHAM LAZARSON.
